WINDING HEAD FOR FLEXIBLE SHAFT
FORMING MACHINES

Clarence F. Hotchkiss, Jr., Binghamton, N. Y.,
assignor to Stow Manufacturing Company, Inc.,
Binghamton, N. Y., a corporation of New York

Original application January 18, 1943, Serial No.
472,770. Divided and this application November
2, 1943, Serial No. 508,755

5 Claims. (Cl. 57—11)

This invention relates to an apparatus and method of manufacturing flexible shafting of the type wherein a central core or wire is wound with one or more successive layers or convolutions of a plurality of wires with the successive layers or wire coats layered up on the core usually composed of a plurality of proper gauge wires and successive layers are usually wound in opposite directions.

An object of the invention is the construction of an apparatus whereby exceedingly long lengths of flexible shafting may be wound up in a semi-continuous manner. That is, the present machine is capable of forming lengths of shafting several hundred feet long and instead of requiring a long building similar to a rope walk the apparatus is considerably compacted whereby a length of shafting twice as long as the building may be wound.

A further object of the present apparatus is the formation of flexible shafting starting with a central core and winding a layer of wire thereon, together with the placing of successive layers over the first wound layer. In operation, the core or previously wound shaft is fed from a reel joined intermediately of two normally equal lengths of shafting in such a manner that only the intermediate section passes through the winding apparatus. That is, as the core or initially wound shafting is fed from a storage reel it is in three or more lengths joined by swivel connections so that the portion of the shafting being wound may be rotated on its longitudinal axis whereby succeeding layers are applied to the rotating section.

A still further object of the present apparatus is the novel construction of a winding head whereby the central core or initially wound cable is rotated on its axis to smoothly and tightly apply a layer or coat of wire thereto and simultaneously advance the wound shafting therethrough.

In the drawings:

Figure 1 is a diagrammatic layout of the entire semi-automatic flexible shaft winding machine for carrying out the features of this invention;

Figure 2 is a side elevation partly in cross-section of the winding head and shafting advancing apparatus;

Figure 3 is a top plan view of the winding head;

Figure 4 is a vertical cross-section taken on line 4—4 of Figure 3 looking in the direction of the arrows;

Figure 5 is also a sectional view taken on line 5—5 of Figure 3 in the direction of the arrows.

It is believed that a general statement and explanation of the apparatus shown in Figure 1 will be of assistance in understanding the advantages and operation of the apparatus as a whole before describing the machine and its associated parts in detail.

Referring to Figure 1, the apparatus comprises generally a rotatable storage reel 1 carrying a core or previously wound shafting 3 and connected thereto by a swivel 5 is a further length of the core or initially wound shafting 7. This section 7 extends over pulleys 9 and 11 with intermediate supporting rollers 13 and, thence, around pulleys 15 and 17. The periphery of the roller 17 is at such a height that the core or wire passing thereover and to be wound is fed directly through a winding tool generally denoted by the numeral 19. A plurality of wires 21 carried on a supply stand 23 are fed into the winding tool 19 where they are wound upon the initial shafting 7 as it is drawn through the tool. Axial rotation is given to this entire section of core 7 and wound section 175 through the medium of a winding head 25. The head 25 imparts rotary movement to the sections 7 and 175 of the shafting and simultaneously pulls or feeds the wound shafting therethrough, the linear movement of the unwound and wound portions of the shafting being indicated by the direction arrows. The previously wound length 27 attached to the wound portion 175 of section 7 passes over pulleys or drums 29, 31 and 33 to a storage reel 35 positively driven by motor 37 and it will be obvious that the swivel 39 between these sections prevents the axial rotative movement between the section of the shifting being wound and the previously wound portion 27 thereof passing to the storage reel.

In the prior art, flexible shafts have usually been wound by stringing up a core and manually carrying along the core a perforated die plate through which wires are fed to lay on the successive convolute layers. Attempts have been made to eliminate these manual operations and to create automatic or semi-automatic machines for carrying out these steps but until the advent of the present invention these prior attempts had not solved the practical difficulties involved particularly those encountered in forming larger diameter flexible shafting. As before stated, this apparatus permits a length of central core wire or a shaft which has been initially wound to be drawn and twisted during its

passage through the machine, whereby a continuous, smooth, tight helix is wound upon the core or initial shaft in such a manner that a shaft of several hundred feet in length can be operated upon before readjusting the machine to carry out a further winding step.

The initial core or previously wound shaft 7 is separated from the remaining material on the reel 1 by a swivel 5, so that the entire length of the core or initial shafting 7 to be operated on turns on its longitudinal axis without imparting rotation to the portion 3. Swivel 39 prevents rotation between wound portion 27 and wound portion 175 of section 7.

The winding head 25 and winding tool or die 19 are mounted intermediate the lower pulleys 15 and 17 on a fixed base and are contiguous to each other. The winding head 25 through which the section 7 and wound portion 175 is drawn and rotated is positively driven by a jack shaft 101 suitably connected by belts or other power-transmitting means to a motor 100. The jack shaft is supported in antifriction bearings 102 mounted in the supporting frame 113. The winding head accomplishes two purposes, namely, the rotation of the shafting whereby the wires 21 feeding through winding tool 19 are layered up or wound upon the core or initially wound shaft and, secondly, the drawing through or imparting linear movement to the shafting as the winding progresses. The winding head per se is shown in detail in Figures 2 to 5, inclusive, and consists of an open box-like frame composed of a pair of channel irons 103 affixed to end plates 104 and 105. The other pair of channels 103' do not extend across the head to the end plates but have their ends joined by bars 140, 141 and 153, 154, as will be hereinafter described.

The end plates 104 and 105 of the box frame are rotatably supported on tubular shafts 120 and 135, respectively. The right-hand hollow axle 120, as shown in Figure 3, is supported within the inner race 106 of a ball bearing having its outer race 108 fitted in a journal 110 affixed in the upper part of frame 113. This end assembly is held in adjusted position by a nut 200 threaded on the tubular shaft 120 inside the cover plate 281.

The left-hand hollow axle 135, the larger diameter portion 204 of which is pressed into a depression in the end plate 105, is supported within the inner race 107 of a ball bearing having its outer race 109 fitted in a journal 111 affixed to the upper part of frame 113. This end assembly is held in adjusted position by a nut 205 threaded on the tubular shaft 135.

The tubular shaft 131 is mounted for independent rotation in spaced bearings 202 and 203. The inner bearing 202 is supported in the larger diameter portion 204 of sleeve 135. The bearing 203 holding the outer end of the sleeve 131 is fitted within an annular opening of flanged cover cylinder 206 and retained in position by nut 207 and cover 208.

A drive pulley 121 is secured on the outer end of the hollow shaft 120 whereby rotative movement is given the entire box frame 103 when the drive pulley 121 thereon is connected to the jack shaft 101. An intermediate belt tightener 122 may be interposed between the jack shaft pulley 166 and frame drive shaft pulley 121.

A similar drive pulley 130 is secured on the tubular shaft 131. The inner end of tubular shaft 131 terminates in a gear 132, so that, when movement is imparted to the driven pulley 130 and hol-

low shaft 131 it freely turns through the end plate and has no effect upon the rotative movement thereof. The end gear 132 meshes with an offset pinion 133 carried on a bolt 134 extending through the end plate 105 and carries thereon a second pinion 136 of smaller diameter also carried on the bolt 134. This reduced diameter pinion 136 meshes with pinion 137 which is of larger diameter and is secured to a horizontal shaft 138 extending from the end plate 105 to a bearing 139 carried on the arm 140 extending between the ends of two of the shorter channels 103'. A similar vertical arm 141 is mounted on the opposite sides of the upper and lower shorter channels 103' in spaced relation to the arm 140 and, between these arms, an axial bolt 142 is mounted carrying a beveled wheel 143. An upwardly extending yoke or fork 150 is also positioned on the axial bolt 142 and carries between its upper sides a non-metallic wheel 151. The end of the yoke 150 is pivotally secured to an adjustable turnbuckle rod 152, having a screw-threaded end passing through an arm 153 which bridges the opposite pair of the shorter box frame members 103'. Secured to the opposite side of the corresponding frame members is a second arm 154 and between these arms is positioned an axle 155 on which is mounted a grooved pulley wheel 156.

The horizontal shaft 138 driven by gear 137 is provided with a worm 158 that meshes with worm gear 159 carried on the shaft 160 journaled between the frame members 103 extending from end plate 104 to end plate 105. A larger diameter pulley 161 is mounted on shaft 160 and positively driven by the worm and gear 158, 159.

In operation, the core or the initially wound cable is threaded through the driven tubular axle 131 and passes over a portion of the grooved freely rotating pulley 156 and in contact with the periphery of the driven wheel 161 and thence over free pulley 143 and outwardly from the winding head through driven axle 120. The shafting is preferably wound around the driven pulley 161 a plurality of turns to insure sufficient frictional contact therewith for continuously and smoothly drawing the shafting through the winding head. This contact is additionally secured by maintaining the periphery of the upper free wheel 151 against the flexible shafting on the driven pulley by means of the pivoted yoke 150 and its adjustable turnbuckle 152. The convolutions of the shafting on the driven pulley are maintained in parallel relation and prevented from overrunning each other by means of a pivoted knife or finger 165 in contact with the shafting as it is started on the pulley 161 through the tension exerted by coil spring 166.

As before stated, the drive pulleys 121 and 130 are rotated from lower parallel jack shaft 101. The power to pulley 121 for rotating the cage or frame of the winding head is taken off from pulley 166 and through suitable belting or the like over belt tightener 122 to the upper pulley. The drive pulley 130 through which the gear chain previously described rotates the shafting advancing drum 161 is similarly driven from the jack shaft through an adjustable speed pulley 167 and belt tightener 168. Normally the drive pulley 130 is driven at a somewhat faster rate of rotation than is the drive pulley 121.

Just prior to the advancing of the shafting through the winding head initially wound shafting 7 passes through the wire laying device 19 where the plurality of strands of wire composing the helix or coat 175 are laid up thereon. The

wound shafting 175 is advanced and rotated as it passes through the winding head 25 and, as before described, the swivels 5 and 39 permit only the initially wound portion 7 and the additionally wound portion 175 of the shafting to rotate.

This novel apparatus of forming large diameter flexible shafting and apparatus for carrying out the method allows exceptionally long lengths of shafting to be manufactured in a semi-automatic manner and within a comparatively small space.

This application is a divisional application of my copending application, Serial Number 472,770, filed January 18, 1943, entitled Apparatus and method for making flexible shafting.

What I claim is:

1. A flexible core winding head including a rotatable frame comprising spaced end pieces joined by horizontal bars, outwardly extending horizontal tubular axles supporting said end pieces, a freely rotatable hollow shaft passing through one of said tubular axles and end pieces, the other of said tubular axles being rigidly secured to the other of said end pieces, a horizontal drive shaft mounted within said frame and connected to the said freely rotatable hollow shaft, a draw pulley pivotally mounted in the said rotatable frame transversely of said horizontal drive shaft and operatively connected thereto, means to independently rotate the said hollow shaft and the tubular axle secured to the frame end piece whereby a flexible core threaded through said hollow shaft and tubular axle and contacting the periphery of said draw pulley will be axially rotated and longitudinally drawn through said winding head.

2. A winding head as defined in claim 1 wherein the inner end of the freely rotatable hollow shaft terminates in an external gear and meshes with one pinion of a gear train terminating in a pinion secured to the end of the horizontal drive shaft adjacent the end piece through which said freely rotatable shaft extends.

3. A winding head as defined in claim 1 wherein a plurality of wheels are mounted in said frame 10 on axles in the parallel plane of said draw pulley and on either side thereof, one of said wheels having a peripheral groove therearound and positioned adjacent the inner end of the said freely rotatable hollow shaft to direct the flexible core 15 threaded through the winding head into contact with the said draw pulley while the other said wheel directs the threaded core outwardly through the aligned tubular axle.

4. A winding head as defined in claim 1 wherein 20 a fork carrying a wheel is pivoted to said frame with the periphery of the wheel yieldably held against the flexible core in contact with said draw pulley, the convolutions of said flexible core being maintained in separate conditions by means of 25 a finger secured to a shaft transversely pivoted across the rotatable frame and pressed into engagement with the periphery of the draw pulley.

5. A winding head as defined in claim 1 wherein 30 the said tubular axles supporting the rotatable frame are mounted in bearings carried on the upper portions of a pair of spaced vertical standards and one of the said tubular axles and the 35 freely rotatable shaft are independently driven from a common jack shaft in parallel relation thereto and carried by the lower portions of said vertical standards.

CLARENCE F. HOTCHKISS, JR.
